HARRY ALBERT STEELE, OF SYRACUSE, NEW YORK, ASSIGNOR TO THE PROSPERITY COMPANY INC., OF SYRACUSE, NEW YORK, A CORPORATION OF NEW YORK.

SPRING PAD FOR PRESSING MACHINES.

Application filed November 24, 1926. Serial No. 150,605.

This invention relates to spring pads for pressing machines and has for its object a particularly simple and efficient spring arrangement by which the springs are assembled and held as a unitary structure without a multiplicity of fastening means so that the padding in use is particularly economical in construction.

The invention consists in the novel features and in the combinations and constructions hereinafter set forth and claimed.

In describing this invention reference is had to the accompanying drawings in which like characters represent corresponding parts in all the views.

Figure 1 is a longitudinal sectional view of a padding embodying my invention, the same being applied to the buck of a pressing machine.

Figure 2 is a fragmentary plan view of this padding, the outer covering being omitted.

Figure 3 is a transverse sectional view, the padding being omitted.

This padding comprises generally a plurality of coiled springs lying on their sides with their coils inclined, the coils of each spring being interlaced with the coils of the next spring. Preferably the padding also includes a plate to which the coils are secured at their ends, and being secured at their ends are held under some tension which tends to hold the springs with their coils at an incline to the plate, so that when pressure is applied to the springs the coils will swing toward the plate and assume at angles of less inclination to the plate.

1 designates the coil springs lying side by side with their coils interlaced as at 2 with the 10 coils of the adjacent springs. 3 is the plate on which the springs are laid side by side with their coils at an incline to the plate. As seen in Figure 1 the lowermost portions of the end coils at like ends of the springs are secured as at 4 to the plate 3, and the uppermost portions of the coils at the other ends of the springs are pulled down and secured to the plate as at 5 so that the coils of the springs normally stand at an incline to the plate due 15 to the tensioning by securing their end coils to the plate in this manner. Owing to the

incline of the coils the coils assume angles of less inclination to the plate, by swinging toward the plate about their points of contact with the plate when pressure is applied to 55 the padding.

The springs are usually covered with the usual layer or wrapper 6 of fabric, felt or other similar covering and this is usually overlaid with another layer 7 of facing material, which is sometimes woven wire cloth 7.

In operation the padding is applied to the buck 8 in any well known manner. The buck 8, as will be understood by those skilled in the art, is carried by or formed integral with, the 60 goose neck 9 rising from a base 10, which is secured to the table or frame of a pressing machine. The construction of the buck forms no part of this invention.

This spring pad is particularly advantageous in that owing to the spring arrangement, it is very simple and economical in construction and at the same time owing to the multiplicity of resilient elements, that is the coils of the springs and their arrangement, 70 the padding is particularly efficient and durable in use and any portion thereof readily yields independently of the other portions or conforms to unevennesses in the garment or other article being pressed.

What I claim is:—

A spring pad construction for pressing machines comprising a plate, a plurality of coiled springs lying on their sides on the plate, the lower portions of the end coils of the springs at like ends of the springs being secured to the plate and the top portions of the end coils at the other ends of the springs being secured to the plate whereby the springs are tensioned with their coils at an incline 90 to the plate, so that the coils when under pressure swing toward the plate, and the coils of each spring interlacing through the coils of the next spring, the intermediate coils between the end coils being free of and slidably engaging the plate.

In testimony whereof, I have hereunto signed my name, at Syracuse, in the county of Onondaga and State of New York, this 21st day of September, 1926.

HARRY ALBERT STEELE.
